Attorney

UNITED STATES PATENT OFFICE.

THOMAS M. HEARD, JR., OF SIOUX CITY, IOWA.

TOOTH-BRUSH.

1,250,454.

Specification of Letters Patent. Patented Dec. 18, 1917.

Application filed August 21, 1916. Serial No. 115,924.

To all whom it may concern:

Be it known that I, THOMAS M. HEARD, Jr., a citizen of the United States, and a resident of Sioux City, in the county of 5 Woodbury and State of Iowa, have invented certain new and useful Improvements in Tooth-Brushes, of which the following is a specification.

The present invention relates to tooth-brushes.

The invention has for its primary object the production of an improved dentifrice-dispensing tooth-brush.

Another object of the invention is the 15 production in a tooth-brush of improved means for applying dentifrice paste thereto.

A further object of the invention is the 20 production of a dentifrice-dispensing tooth-brush embodying certain novel features of construction whereby the dentifrice-retaining portion of the brush may be readily detached from the back of the brush to permit the introduction of a new dentifrice tube, or the attachment of a new brush.

25 Furthermore, the invention contemplates a dentifrice-dispensing tooth-brush particularly adapted for using collapsible tubes and embodying certain features to conserve the dentifrice.

30 Furthermore the invention has for an object the production of an improved dentifrice-dispensing tooth-brush inexpensive in manufacture, durable and thoroughly efficient in operation.

35 Still a further object of the invention is the production of a tooth-brush which facilitates the application and thereby stimulates the use of dentifrice.

With these and other objects in view, the 40 invention, consisting in the construction, combination and novel arrangement of parts, will be fully understood from the following description, reference being had to the accompanying drawings, which form a part of 45 this application and in which like characters of reference indicate corresponding parts throughout the several views, of which,—

Figure 1 is a side elevation of a tooth-brush constructed in accordance with the 50 invention;

Fig. 2 is a longitudinal section of the same;

Fig. 3 is a side elevation of the handle de- 55 tached; and

Fig. 4 is a perspective view of the collapsible tube follower.

Although I have illustrated and herein-after described the preferred embodiment of the invention, I would not be understood as being limited to the specific structure chosen for illustration for it will be apparent that various alterations and modifications may be made without departing from the spirit and scope of the invention 60 as defined in the appended claims.

Referring, now, to the illustrations, 5, represents the back of the brush provided with the usual bristles, 6. The back is formed with a relatively short cylindrical 70 shank, 7, provided with an axial bore, 8, threaded to receive the neck, 9, of a collapsible dentifrice tube, 10. The back is provided with a duct, 11, which communicates with the bore, 8, and the bristled face to convey the dentifrice to the bristles.

The handle is a cylindrical tube, 12, adapted to freely inclose the collapsible tube and provided with an internal, annular flange, 13, adapted to be engaged with in a peripheral groove, 14, in the shank of the back. Opposite sides of the handle are provided with longitudinal slots, 15, and the flanged end is sheared as at 16, into the slots thereby permitting the handle or case to be 80 sprung open as indicated in dotted lines in Fig. 3 to permit access to the case and convenient detachment and attachment of the brush.

The sheared end of the case is normally 90 encircled by a band, 17, provided with a bayonet slot, 18, adapted for engagement with a lug or stud, 19, on the case. The band secures the case to the brush and yet permits relative rotation between the case 95 and the brush, and removal of empty and insertion of full tubes.

Within the case is a follower adapted to be impelled in the direction of the brush by rotation of the handle to expel the dentifrice 100 from the tube. In the present embodiment this follower consists of a cylindrical nut, 20, having lugs or ears, 21, engageable within the slots, 15, to prevent relative rotation between the handle and the nut. The face 105 of the nut is provided with a concave or conical recess, 22, and an axial bore, 23, threaded to screw upon the reduced end of the collapsible tube.

In operation, the band, 17, having been 110

slid off the handle, the latter is sprung open. The brush is then screwed into the neck of a collapsible tube, and the opposite end of the tube, previously reduced and twisted is introduced into the follower nut. The nut is then turned and as it cuts threads on the twisted end of the tube, it moves toward the brush. The tube is then inclosed within the handle and the handle replaced on the brush.

10 It is evident that by rotating the handle, the nut is forced toward the brush, thereby expelling the dentifrice into the brush.

The recessed face of the follower serves to gradually reduce and twist the end of 15 the tube.

Having thus described my invention, what I claim as new and desire to secure by Letters Patent of the United States, is,—

1. A tooth-brush comprising a back and 20 bristles thereon, a hollow handle rotatably secured to the back and adapted to freely inclose a collapsible dentifrice tube, the back being adapted to be secured to the tube and convey the dentifrice to the bristles, and a 25 follower nut movable longitudinally within and fixed to turn with the handle, adapted to be screwed onto and reduce the tube by rotation of the handle.

2. A tooth-brush comprising a back with 30 bristles thereon, a cylindrical hollow handle rotatably and detachably secured to the back and adapted to freely inclose a collapsible dentifrice tube, the back being adapted to be secured to the tube and convey denti-

frice to the bristles, the handle being slotted 35 longitudinally, and a cylindrical studded nut engaged with the slotted handle movable longitudinally thereof and adapted to thread upon and thereby reduce the tube to expel the dentifrice by rotation of the 40 handle.

3. A tooth-brush comprising a back with bristles thereon, the back having a cylindrical shank provided with a peripheral groove, and an axial bore threaded to receive the 45 neck of a collapsible dentifrice tube, the back having a duct to convey the dentifrice to the bristles, a hollow cylindrical handle adapted to freely inclose the tube, and having an internal annular flange at one end 50 freely engaged within the groove to rotatably secure the handle to the shank, opposite sides of the handle being slotted longitudinally and the flanged end being sheared longitudinally into the slots to permit 55 spreading of the handle, a band removably encircling said end to normally prevent spreading of the handle, a cylindrical nut movable longitudinally within the handle and having studs engaged within the slots, 60 said nut being adapted to screw onto a reduced end of the tube, and provided with a recessed face to facilitate the reduction of the tube as the nut is screwed thereon.

In testimony, whereof, I have hereunto 65 set my hand this 16th day of August, 1916.

THOMAS M. HEARD, JR.
